UNITED STATES PATENT OFFICE.

RICHMOND W. WHEELER AND SILAS Q. DUNTLEY, OF BUSHNELL, ILLINOIS,
ASSIGNORS TO BUSHNELL PUMP COMPANY, OF SAME PLACE.

PUMP-BUCKET.

SPECIFICATION forming part of Letters Patent No. 333,802, dated January 5, 1886.

Application filed August 26, 1885. Serial No. 175,385. (No model.)

To all whom it may concern:

Be it known that we, RICHMOND W. WHEELER and SILAS Q. DUNTLEY, both of Bushnell, in the county of McDonough and State of Illinois, have invented certain new and useful Improvements in Pump-Buckets, of which the following is a full, clear, and exact description, reference being had to the accompanying drawings, forming part of this specification, 5 in which—

Figure 1 is a front elevation of our pump-bucket. Fig. 2 is a side elevation with part broken away to show the clamping attachment. Fig. 3 is a vertical section on line 3-3, 15 Fig. 2. Fig. 4 is a perspective view of the inside of the cup. Fig. 5 is a perspective view of the bucket-packing. Fig. 6 is a perspective view of the outside of cup with part broken away to show one of the apertures for 20 introduction of the clamping device. Fig. 7 is a detail section bottom view of cup, showing the relative position of the divergent notches in connection with the slots or apertures in cup. Fig. 8 is a modification showing a perspective view of the outer cup with the coupling 25 projections on inside. Fig. 9 is a detail section of a modification, showing shoulder on strap on inside and projection on outside, and also the rabbeting of the packing.

30 Our invention relates to certain improvements in pump-buckets; and our invention consists in features of novelty hereinafter fully described, and pointed out in the claims.

The advantages of our bucket over all 35 wooden buckets is in its strength and durability, its ready adjustment, and attractive appearance, and over other metal buckets is its rigid clamping device, ease of adjustment, strength, and cheapness of construction.

40 Referring to the drawings, similar letters of reference in the various figures indicate like parts.

A represents the outer cup of the bucket, and A' the inner cup.

45 A² are lugs or projections on the outside of the inner cup, shown as our preferable plan, (see Fig. 4,) or on the inside of the outer cup, shown as a modification, (see Fig. 8.) These projections engage in perforations B² in the 50 bucket-packing B, and secure it in its position.

B' is the rabbeted portion of the bucket-packing, into which the outer cup fits, thus embedding the cup in the packing, so as not to interfere with its friction surface.

C are the straps or shanks that serve as a 55 bail to the bucket and attach it to the rod or staff D.

C' C are rivets or bolts that secure the straps to the rod, and C² are threaded nuts that engage the bolts.

50 E is a valve seated in the inner cup.

F F F F are perforations through corresponding portions of the cups, with notches F' F' F' F' that relatively alternate in their divergent positions at the opposite sides of the 65 cups, and relatively also in the connection of the cups themselves, as shown in Figs. 4 and 6, so that when the cups are placed in position the divergent notches in one cup will invariably be covered by an unperforated portion 70 of the corresponding cup. (See Fig. 7.) It will be seen that these perforations and notches together form key-hole slots, by which name they are hereinafter referred to.

75 G is a shoulder or lug on the strap, fitting, when in position, on the seat of the inner cup, and G' a similar lug fitting below the outer cup. In our preferable plan we place the upper lugs on the outside of the strap and the lower ones on the inside, as shown in Figs. 1 80 and 3; but we do not confine ourselves to such relative positions, for it is evident that the position of the lugs may be reversed, the upper lug then being on the inside of the strap and the lower one on the outside, as shown in Fig. 85 9, without deviating from the essential features of our invention. In other words, each shank must have two lugs, which must project from opposite sides of its axis, one toward and one from a line drawn through the axis 90 of the bucket at right angles to a line drawn through the perforations.

We will proceed to describe the operation of our invention in reference to our preferable form of the device, and from which also 95 the modified or opposite forms thereof may be readily understood. The bucket-packing is placed around the inner cup, the projections on the out flange of which enter perforations in the packing and secure it there. The lower 100

ends of the strap irons or shanks are passed through the perforations F in the inner cup, the lower lugs being presented so as to pass through the divergent notches in connection with said perforations. The strap-iron then receives a half-turn, which brings it into position when the outer cup is rightly presented for the said lugs to pass through the notches in connection with the perforations as the end of the shank-iron passes through the cup into its seat. The strap is then turned a quarter round, bringing it in position to attach to the rod and in the direction to bring the lower lugs in position presenting inward toward each other, 15 when the upper lugs will present outward, as shown in Figs. 1 and 3. When the end of the rod D, which may be wedge-shaped or not, as desired, is inserted between the strap-irons and brought home to its position, the straps are 20 pressed apart at top, and are thus made to exert a leverage in connection with the clamping-lugs to tighten the corresponding cups and bucket-packing and insure a stiff tight joint, in which, as there is no movement, (as when 25 elastic packing is used,) there can be no wear. On the other hand, where elastic packing is used between the cups, of necessity there must be movement and consequent friction and wear. The rabbeted bucket-packing provides a 30 recess for the flange of the outer cup, so that it does not interfere with the friction-surface of the packing.

The parts of the modified form being the reverse of those just described, it is obvious 35 that to cause the upper lugs, G, to exert a downward and the lower lugs, G', an upward pressure, the upper ends of the straps or shanks C must be drawn together instead of being forced apart; hence, to state it broadly, 40 the shanks C must be forced and held in the direction in which their respective upper lugs project.

We are aware that in constructing pump-buckets the two bottom disks, between whose 45 peripheries the packing is secured, have been provided with coincident elongated slots, through which the respective members of the bifurcated extremity of the sucker-rod are passed. Each of these members (or shanks) 50 is provided with an annular collar, which, when the parts are secured together, rests upon the upper surface of the upper disk, and a lateral enlargement at its lower extremity corresponding in shape to the elongated slots 55 through the disks, and occupies a position transverse or at an angle to said slots. This is not, however, the equivalent of our invention. With this device, in order to secure a tight joint and prevent rattling and leakage,

a rubber packing must be interposed between 60 the two disks, which is put under compression when the parts are secured together, and afterward exerts its force in holding the two disks apart and against the upper and lower enlargements of the shanks. It is well known 65 that rubber retains its elasticity but a very short while when used for this purpose, and it is the object of our invention to do away with it entirely and still produce a perfectly tight joint between the parts. Again, by forming 70 the body of the perforations through which the shanks pass cylindrical, and arranging the notches in the respective disks alternately, as described, the aperture through the bottom of the bucket, considered as a whole, 75 is cylindrical, (see Fig. 7,) and is completely closed by the cylindrical portion of the shank.

We claim as our invention—

1. In a pump-bucket, the combination, with 80 the packing and a pair of disks having slots, of a pair of straps or shanks each having a pair of lugs located, respectively, above and below said disks, and projecting from opposite sides of its axis, one toward and the other from a line drawn through the axis of the bucket at right angles to a line drawn through the apertures, said shanks being forced in the direction in which their respective upper lugs project and held by bolts 90 to the sucker-rod, as set forth.

2. In a pump-bucket, the combination, with 95 the packing and a pair of disks having key-hole slots F F', said disks being so arranged that the cylindrical portions F of said slots coincide while the notched portions F' alternate, as described, of the shanks C, each having a cylindrical portion for filling the cylindrical portion of said slots, and a pair of lugs, G G', located, respectively, above and below 100 said disks, substantially as set forth.

3. In a pump-bucket, the combination, with 105 the packing and a pair of disks each having key-hole slots arranged with their cylindrical portions coincident and their elongated or notched portions alternate, as explained, of the shanks C, each having the lugs G G', located, respectively, above and below said disks and projecting in opposite directions, and the rod D and bolts C' C'', for forcing and 110 holding the upper portions of said shanks in the directions in which their respective upper lugs, G, project, as explained.

RICHMOND W. WHEELER.
SILAS Q. DUNTLEY.

In presence of—

WILLIAM RIEPEN,
T. H. WHEELER.
